ATT'YS.

UNITED STATES PATENT OFFICE.

RALPH D. PARKER, OF SAN FRANCISCO, CALIFORNIA.

DESIGN FOR AN AUTOMOBILE WINDSHIELD WING.

60,808.

Specification for Design.

Patented Apr. 11, 1922.

Application filed July 13, 1921. Serial No. 484,498. Term of patent 3½ years.

To all whom it may concern:

Be it known that I, RALPH D. PARKER, a citizen of the United States, residing at San Francisco, in the county of San Francisco and State of California, have invented a new, original, and ornamental Design for Automobile Windshield Wings, of which the following is a specification, reference being had to the accompanying drawing, forming part thereof.

The figure is a front elevation of an automobile windshield wing, showing my new design.

I claim:

The ornamental design for an automobile windshield wing, as shown.

RALPH D. PARKER.
